DESIGN FOR A JAR

John F. Toner, Denver, Colo., assignor to Owens-
Illinois Glass Company, Toledo, Ohio, a corpo-
ration of Ohio

Application August 27, 1936, Serial No. 64,587

Term of patent 14 years

To all whom it may concern:

Be it known that I, John F. Toner, a citizen of the United States, residing at Denver, in the county of Denver and State of Colorado, have invented a new, original, and ornamental Design for a Jar, of which the following is a specification, reference being had to the accompanying drawing forming a part thereof.

In the drawing:

Fig. 1 is a side elevational view of a jar showing my new design.

Fig. 2 is an end elevational view thereof.

Fig. 3 is a bottom plan view thereof.

I claim:

The ornamental design for a jar substantially as shown.

JOHN F. TONER.
